COMBINED FUEL INJECTION PUMP AND
NOZZLE FOR INTERNAL COMBUSTION
ENGINES

Joseph F. Geiser, Providence, R. I.

Application March 25, 1935, Serial No. 12,911

1 Claim. (Cl. 299—107.2)

This invention relates to fuel injectors for internal combustion engines, and has for the primary object the provision of a device of this character which will utilize the compression of an engine to compress and force fuel into the engine, being suitably actuated to admit the fuel at proper time to the engine or after the completion of the compression stroke of the piston and at the beginning of the working stroke of the piston, and which thoroughly atomizes the fuel and introduces the atomized fuel to the engine under desired pressure against the motivating pressure of the engine.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating an injector adapted to a fragmentary portion of an engine and constructed in accordance with my invention.

Figure 2 is a fragmentary horizontal sectional view showing means for mechanically opening and closing the injector to the combustion chamber of the engine.

Figure 3 is an exploded fragmentary perspective view of a feed nut and valve carried thereby and a fuel tube.

Figure 4 is a fragmentary vertical sectional view showing the injector closed to the combustion chamber and free of the compression of the engine.

Referring in detail to the drawing, the numeral 1 indicates a fragmentary portion of an engine wherein the cylinder is indicated by the character 2, the intake and exhaust valves by the characters 3 and 4, the cylinder being closed by a head 5 and reciprocating in the cylinder is a piston 6. In the cylinder, between the piston and the head 5 is the firing chamber of the engine and the head is constructed to receive an injector 7 forming the subject matter of the present invention.

The injector includes a housing 8 mounted in a passageway formed in the head 5 with its inner end terminating in the firing chamber of the engine and closed except for a port 9 placing the interior of the housing in communication with the combustion chamber. A head 10 is removably secured to the head 5 and overlies the outer end of the housing 8. Integral with the

head 10 is a stem 11' which projects into the housing and spaced therefrom. The stem is equipped with a bore 12 communicative with a chamber 13 in the head 10. A fuel supply pipe 11 connects to the head 10 and is in communication with the chamber 13. A check valve 14 is located in the chamber for closing the fuel pipe 11 against back pressure but which will permit fuel to flow into the bore 12 of the stem. A check valve 15 similar to the check valve 14 is located at the inner end of the bore 12. An elongated cylindrical piston 16 is journaled in the housing 8 and has a frictional fit with the stem 11' and is capable of rotating and sliding relative to the stem. A coil spring 17 in the head 10 acts against the piston 16 to urge the latter in the direction of the inner end of the housing. A gear 18 is splined to the outer end of the piston and meshes with a rack bar 19. The rack bar is connected to a suitable timing mechanism (not shown) of the engine for the purpose of imparting, at timed intervals, oscillatory movement to the piston.

The inner end of the piston carries a nozzle or a jet 20 arranged in alignment with the port 9 and this jet is opened and closed by a needle type valve 21 slidably mounted in a sleeve 22 forming an integral part of a feed nut 23. The feed nut is splined to the inner end of the stem 11' and the threads thereof mesh with threads 30 formed on the piston. The sleeve, feed nut and inner end of the stem 11' form a fuel chamber 24, the latter being closed to the jet 20 by the spring pressed needle valve 21.

The piston 16 is moved endwise in one direction by the compression developed by the piston 6 of the engine and is moved endwise in an opposite direction by the action of the spring 17. The reciprocation of the piston 16 develops a partial vacuum which acts to draw fuel into the fuel chamber 24 passing the check valves and said fuel is compressed by the reciprocation of said piston 16 and delivers said compressed fuel to the combustion chamber of the engine. The timing mechanism imparts rotation to the piston 16 in one direction when the piston completes its compression stroke so that the feed nut is caused to move endwise disengaging the needle valve 21 from the nozzle, placing the fuel chamber 24 in communication with the combustion chamber of the engine so that the fuel compressed in the fuel chamber 24 will be ejected to the combustion chamber of the engine. It is to be understood that passages 25 are provided between the nozzle or jet 20 and the fuel chamber 24. After

- the firing of the fuel in the combustion chamber of the engine, the timing mechanism (not shown) imparts a reverse rotation to the piston, bringing about closing of the nozzle or jet by the needle 21. The piston 16 returns to its initial position against the inner end of the housing when the piston 6 of the engine is on its exhaust stroke causing a vacuum in the fuel chamber and sucking in the fuel through the check valves.
- 10 Having described the invention, I claim:
- An injector comprising a housing having a port at one end thereof, a hollow stem extending into the housing, a head for said stem, a fuel supply pipe in communication with the stem, a piston 15 rotatably and slidably mounted in the housing

and having a frictional fit with the stem and provided with feed threads, a feed nut slidably connected to the stem and meshing with the feed threads of the piston, a sleeve having passages carried by the feed nut and cooperating with the latter and the stem in defining a fuel chamber, a nozzle carried by the piston, a self-seating valve carried by the sleeve for opening and closing the nozzle, a spring engaging the piston carried by the head for effecting movement of the piston in one direction, a gear on the piston, and a rack bar engaging the gear and movable at timed intervals for effecting oscillation of the piston to engage and disengage the valve with the nozzle. 5 10
